1

This invention relates to the purification and concentration of hydrocarbon sulfonates of the oil-soluble or "mahogany acid" type, and to the conversion of these sulfonates to polyvalent metal sulfonates.

In the preparation of some rust preventing compounds and lubricants, and in the preparation of some lubricants for severe service uses and for similar lubricating uses, it has been a practice for many years to employ various metal salts of sulfonic acids derived from the reaction of sulfuric acid and petroleum fractions in the lubricating oil range. These sulfonic acids, and their salts are well known in the petroleum industry. Those most commonly used for the present purpose are the oil-soluble acids known as "mahogany acids" which are found in solution in a supernatant oil layer which accumulates above an acid sludge layer upon settling of a batch of petroleum lubricating oil following sulfuric acid treatment. The sulfuric acid treatment of petroleum lubricating oil results also in the production of other sulfonic acids, known as "green acids," which are primarily water-soluble and are, therefore, found chiefly in the acid sludge layer. However, some of these water-soluble green acids are found in the presence of the oil-soluble mahogany acids in the oil layer and are objectionable for certain purposes. Possibly these vagrant water-soluble sulfonic acids pass into the oil layer because they are at the same time slightly oil-soluble, or because they are to that extent solubilized by the action of the mahogany acids, or because of the failure to remove the last traces of "pepper sludge" from the acid-treated oil. As a result, these objectionable water-soluble green acids are carried over as sulfonate into the oil-soluble sulfonate which is commonly placed upon the market as the sodium salts of the mahogany acids. For the purpose of preparing rust preventing compounds and severe service lubricants, these sodium mahogany acid salts are commonly converted by metathesis into alkaline earth metal sulfonates, usually the calcium salts. The calcium salts of the true mahogany acids appear to be almost entirely insoluble in water although oil-soluble. But the resultant calcium salts of the green acids, which are readily water-soluble, are apparently also oil-soluble in the presence of mahogany acid salt. Because of their water-solubility, they are objectionable in rust preventives and in lubricating oils where moisture may be encountered, because they appear to weaken the resistance to water of an oil film on metal, possibly through

5 favoring the formation of a water-continuous emulsion; whereas the water-insoluble, oil-insoluble calcium salts of the true mahogany acids, when operating in the presence of water to form emulsions, result in emulsions where oil is the continuous phase.

10 In the case of oil-continuous emulsions, the oil preferentially wets iron or steel surfaces with the result that the water present in the emulsion does not wet the metal and rusting is avoided. On the other hand, where the chemical environment produces water-continuous emulsions, the water phase displaces the oil from the metal surface, thereby reducing or destroying the rust inhibiting effect of the oil.

15 Even though the oil-soluble, water-insoluble sulfonates greatly predominate, nevertheless, appreciable proportions of water-soluble sulfonates result in undesirable effects when the polyvalent-metal sulfonates are used as detergent additives or rust preventives in lubricants. For example, even a relatively small proportion of the water-soluble sulfonate results in excessive water corrosion, to the extent that products fail to give the full degree of protection required in severe service, such as in military and naval operation.

20 In my prior Patent 2,453,690 entitled Process of Producing Polyvalent-Metal Hydrocarbon Sulfonate, issued November 16, 1948, I disclosed a process of converting and treating oil-soluble, water-insoluble, polyvalent-metal petroleum sulfonates, such as calcium petroleum sulfonate in oil in the presence of water with an oil-soluble, liquid, emulsion-breaking, organic compound, such as a butyl, amyl, or hexyl alcohol, whereby 25 to break the resultant emulsion, to cause much of the objectionable water-soluble "green acid" sulfonates to separate in a resultant water layer and thereby correspondingly purify the oil solution of the desired oil-soluble "mahogany acid" sulfonates, and to provide for separation of objectionable water-insoluble, inorganic salts, such as resultant calcium sulfate, which was accomplished by filtering the resultant oil-sulfonate layer in the presence of a filter aid, or the like.

30 35 40 45 It is an important object of the present invention to purify alkali-metal mahogany sulfonates by ridding them of the mentioned objectionable substances, to concentrate such mahogany sulfonates with respect to oil by eliminating excess oil therefrom, and then to convert to polyvalent-metal forms the mahogany sulfonates so purified and concentrated in order that they may be useful in corresponding rust preventives and detergent lubricating oil.

50 55 Another object is to separate the green acid

sulfonates and inorganic sulfates or other inorganic salts which would form insoluble salts with calcium or other polyvalent metal to be used, as water-soluble forms in a water and emulsion-breaking liquid layer from which the oil and water-soluble, alkali-metal mahogany sulfonates present are caused to separate.

It is also an object to provide a process for recovering oil-soluble, water-insoluble, polyvalent-metal sulfonates, such as calcium mahogany sulfonates, in oil, whereby excess oil beyond that desired in a given product is easily rejected in the presence of water and an oil-soluble, emulsion-breaking, organic liquid, such as an amyl, hexyl, or butyl alcohol. A particular object is to remove excess oil before conversion of the mahogany sulfonate to the water-insoluble, polyvalent-metal form.

It is also an object to separate the objectionable inorganic salts mentioned in a water-soluble form whereby to avoid the necessity of subsequently filtering their insoluble forms from the oil-sulfonate product, and whereby to reduce employment of filter aid and the like and the incidental costs thereof.

It is a still further object of the invention to provide a process for the recovery of petroleum sulfonates whereby formation of difficulty breaking emulsions, such as the large so-called "cuff" layers, is avoided.

Still another object of the invention is to provide a process for the treatment of crude petroleum sulfonates containing excessively large percentage amounts of petroleum oil, appreciable amounts of water and objectionable inorganic salts and "green acid" sulfonates, whereby the objectionable materials and excess petroleum oil are easily eliminated.

Thus, individual objects are: to eliminate all green acid sulfonates; to eliminate all objectionable inorganic salts easily and without excessive employment of filter aid; to eliminate easily any proportion of excess oil from the sulfonates; and to provide such a process adaptable to the usual crude sodium sulfonates containing, for example, up to 80% or 85% mineral oil of various lubricating viscosities and from perhaps 0% to 50% or 60% water based on oil-sulfonate content along with 1% to 5% of inorganic salts such as sodium sulfate and sulfite.

It is also an object to purify and/or concentrate crude alkali-mahogany sulfonate for use as emulsifying and wetting agents or for other known uses to which sodium, potassium and/or ammonium hydrocarbon sulfonates and sulfates are put.

It is also an object to provide a purification, concentration, and conversion process for crude sulfonates of the indicated character whereby very large batches of crude material of high oil content and relatively low sulfonate content may be so treated with relative ease, as against treatment of only relatively small batches as heretofore.

Other objects of the invention will become apparent from the following description, as will the various features of the invention. In connection with the following specification reference is made to the accompanying drawings wherein:

Fig. 1 is a flow diagram representing the major steps of the process when operated batchwise;

Figs. 2, 3, and 4 present curves for secondary butyl alcohol treatments at 145° F., 185° F. and 100° F., respectively, which curves show various relationships among various component mate-

rials present during the operation of the process;

Fig. 5 is a flow diagram representing the principal steps of the process when operated continuously in single or multiple stages; and

Fig. 6 is a flow diagram representing the principal steps of the process when operated countercurrently.

Throughout this specification, the term "water-insoluble" is intended to signify relative insolubility, that is, entire immiscibility or only partial miscibility under the conditions employed, as contrasted with complete miscibility in any proportion. The term "water-soluble" is used to signify either true (complete) solubility or a high state of dispersion which approaches true solubility and is adequate for the respective purpose. The term "oil-soluble" signifies substantially true or complete solubility of the respective material in the hydrocarbon oil present or a high state of dispersion approaching such true or complete solubility. The term "soap" will sometimes be used to signify the respective sulfonate. Where reference is made to removal or elimination of green acid soaps or inorganic salts, such terminology is intended to include either complete elimination or reduction of the respective materials to such insignificant proportions that the presence of the remainder does not interfere seriously with subsequent processing or is not detrimental for uses to which the sulfonate product is eventually to be put. Where the term "concentration" is used, it refers to the concentration of the sulfonates with respect to the oil present unless some other meaning is obvious.

In treating crude petroleum sulfonates, various crude materials are encountered, all of which are amenable to the process of this invention. These crude sulfonates commonly contain between 30% and 85% petroleum oil of various lubricating viscosities, various sulfonate contents between about 10% and about 60% soap including between about one-half per cent and 3% green acid soaps, and from 1% to 5% (for example, 3%) of sodium sulfate and sodium sulfite of which the sulfate predominates. The sulfonates are commonly salts of the alkali metal sodium and are water-soluble. They are to be purified to eliminate the green acid soaps, the sulfites and sulfates mentioned, the water, and any proportion of the oil which is not desired in the final product and which will be ordinarily referred to herein as "excess oil." The green acid soaps are to be removed because of their deleterious effects in the end products, and the sulfites and sulfates are to be removed because they interfere with the emulsifying properties of the sodium sulfonate and constitute impurities therein if permitted to remain. In addition, if these inorganic sulfates and sulfites are retained, they are converted into insoluble polyvalent-metal compounds in the conversion stage and settle to the bottom of the treating tank as a mud which, in the presence of the sulfonates, is coated with considerable quantities of oil because of the wetting properties of the sulfonates and presents here the problem of difficult separation or the element of unnecessary loss of a substantial proportion of oil and sulfonate.

My present invention involves certain new discoveries that I have made. Thus, I have found that, at appropriate temperatures, I am able to purify crude, water-soluble, alkali-metal sulfonates before conversion to the water-insoluble, polyvalent-metal forms by commingling them with controlled proportions of water and of an

emulsion-breaking, oil-soluble, relatively water-insoluble organic liquid, the objectionable inorganic salts and green acid sulfonates passing into a water layer which settles out as a brine upon standing. Such treatment may be effected with very large gallonage and is facilitated where the water is present as a weak sodium chloride solution, for example a 5% solution.

I have also discovered that excess oil may be separated from the water-soluble alkali-metal sulfonate by controlling the proportions of water and emulsion-breaking liquid respectively to the soap-oil content of the crude sulfonate. Generally, by holding the proportion of emulsion-breaking liquid constant at a low level between 5 and 25 volumes per 100 volumes of soap-oil mixture (reckoned together) in the crude stock and adding water in increasing amounts, first a brine phase appears which settles to the bottom and may be drawn off as indicated above. Further additions of water cause an oil phase to appear which rises to the top and is readily separated from the then concentrated soap layer. This rejected oil phase contains only a fraction of a percent of soap but does contain a few percent of the emulsion-breaking liquid and water. The rejection of the excess oil is increased as the proportion of either the emulsion-breaking liquid or water, or both, is increased, and appears to be practically independent of whether or not the brine phase is removed as soon as it appears; but unless the brine phase is removed after appearing, it will go back into solution upon further addition of alcohol and water.

The production of both a brine layer containing undesirable inorganic salts together with green acid soaps and a rejected oil layer containing excess oil can often be accomplished in one step by careful selection of the treating doses of water and emulsion-breaking liquid, respectively. However, for greatest flexibility and ease of operation by less skilled personnel, it is usually preferred to conduct the purification and oil separation as separate steps, differing from each other mainly in the amount of water present. Reference to Figs. 2 and 3 will show for example that, with a given amount of secondary butyl alcohol within a suitable range with respect to the oil-soap content of the stock, a brine layer will appear upon increasing the water present (curves B) before a rejected oil layer will appear (curves A). However, continued increase of the water beyond a certain point causes the brine layer to decrease and eventually disappear; whereas when the critical amount of water has been reached to cause appearance of a rejected oil phase, further additions of water cause increasing amounts of oil to be rejected and the total amount of oil rejected tends ultimately to approach asymptotically the total amount of oil present in the stock. Likewise, as shown in Figs. 2, 3 and 4 (curves C and D), at a given water content up to a certain point, the yield of brine phase increases slightly with alcohol dosage, but beyond this point increasing dosages of alcohol result in decreasing yields of brine, whereas after the rejected oil layer appears, the yield of rejected oil continues to increase with increasing dosages of alcohol at a constant water dosage, at least within the range of alcohol preferred in this invention.

I have also discovered that after the removal of any brine layer settling to the bottom and the separation of the rejected oil which rises as a supernatant layer, the alkali-metal soap in the

75 soap-oil concentrate layer which contains the water and the emulsion-breaking liquid, may be easily converted to water-insoluble, oil-soluble, polyvalent-metal soap by mixing therewith a water solution of a salt of an appropriate polyvalent metal, the mixture being allowed to stand at appropriate temperatures for a moderate time whereupon sharp separation results between the polyvalent-metal soap and oil layer and the aqueous layer.

10 It is apparent that my invention comprises a complete process whereby the crude mahogany acid sulfonates are (1) purified by removing inorganic salts and green acid soaps in the form of an aqueous brine, (2) concentrated by rejecting and removing excess oil, and (3) converted to polyvalent-metal sulfonates. These three steps are efficiently controlled by the proper adjustment of three variables; namely, variation of the proportion of water, as above indicated, employment of an appropriate proportion of emulsion-breaking liquid, and operation at a suitable temperature.

15 Generally temperature is not a critical variable; however, temperature ranges in the neighborhood of 140° F. to 150° F. when the various operations are conducted batchwise and 180° F. to 200° F. when conducted in a continuous manner, for each of the purification, concentration, and conversion steps are conveniently employed.

20 Efficient proportions of emulsion-breaking liquid ordinarily range from about 5 parts to about 20 parts for each 100 parts of soap-oil (reckoned together) in the crude sulfonate to be treated.

25 As to water contents, while different stocks have somewhat different requirements, as is always true in any type of treatment of petroleum fractions or derivatives, nevertheless, 30 in general, approximately 20 parts to 50 parts of water (preferably largely sodium chloride solution), are effective in the purification stage for each 100 parts of soap-oil (reckoned together) in the crude stock to remove objectionable inorganic salts, sodium sulfate and sodium sulfite, and the undesired green acid sulfonates. In the concentration stage, additional water is supplied if insufficient excess oil has been rejected during the purification step. Ordinarily, 30 to 50 parts 35 of water total per 100 parts of soap-oil (reckoned together) in the crude stock to be treated will give suitable rejection of excess oil.

40 Additions of either water or the emulsion-breaking organic liquid or both to a mixture 45 whose composition is in the range for oil rejection will disturb the solvency equilibrium and cause additional rejection of oil into the supernatant layer. The resultant underlying concentrated soap layer (soap concentrated with respect to oil) may thus be made to contain oil in that 50 proportion desired in the final product.

55 I have discovered that instead of using practically pure water (city drinking water), along with the emulsion-breaking liquid, to wash out 60 water-soluble impurities from a crude sodium sulfonate-oil mixture, I can advantageously use an aqueous salt solution in many instances. Where it is expected that purified sodium sulfonate will subsequently be converted to calcium, barium, or strontium sulfonate, it is very desirable to remove sulfates and sulfites as far as practical to avoid formation of the water-insoluble sulfates and sulfites of these polyvalent metals during the conversion of the soap. The presence of anions which 65 do not give water-insoluble salts with the poly-

valent metals is not objectionable from this standpoint, such anions being chlorides, nitrates, acetates, etc. Therefore, if the presence of these anions in the wash water effects greater removal of the sodium sulfate and sulfite in the brine layer during the purification step, their use is often justified. In general, chlorides of the monovalent metals are preferred, especially sodium chloride because of both its efficiency and relatively low cost. When using sodium chloride solution in place of water during purification, the same behavior is obtained as is illustrated by the curves in Figs. 2, 3, and 4, except that the amount of brine phase settling out for a given dosage of alcohol and water, respectively, is both larger in volume and more concentrated in sulfates and sulfites.

If a purified concentrated alkali-metal sulfonate is desired as the end product, the concentrated soap layer is simply distilled to remove water and the emulsion-breaking organic liquid, and the resulting residue is recovered, with or without final purification by filtering or centrifuging while heated.

If a purified concentrated polyvalent-metal sulfonate is desired as the end product, the concentrated soap layer is reacted with an appropriate water-soluble polyvalent-metal salt such as calcium chloride. Usually the polyvalent-metal salt is added in the form of a concentrated aqueous solution, but with proper agitation the solid salt in the form of flakes, powder, or crystals, may be added directly to the concentrated soap layer. On account of the presence of the emulsion-breaking organic liquid, the reacted mixture stratifies readily into a converted soap layer, containing also the remaining oil and most of the emulsion-breaking organic liquid, and an aqueous phase containing by-product salts, excess reagent salt, and a very small proportion of emulsion-breaking organic liquid. The converted soap layer is separated and distilled to recover emulsion-breaking organic liquid and finally dehydrated and recovered as the end product after filtering or centrifuging while heated.

While temperatures are not particularly critical, as mentioned before, nevertheless, at temperatures materially below 140° F., viscosity conditions become a consideration because they delay phase separation, and at low temperatures such as around 100° F., the separation of the various phases is inconveniently slow. However, if the time element is of little consequence, temperatures may be used down to 100° F., for example, without difficulty, as is apparent from the curves of Fig. 4. While temperatures as high as 185° F. and up to about 200° F. produce rapid settling, they, nevertheless, may complicate the matter of maintaining adequate concentration of the emulsion-breaking liquid in batchwise operations. Therefore, a temperature of about 145° F., or from about 140° F. to 150° F., has been found to be a desirable optimum and representative of a good compromise between speed of separation and settling of the layers and retention of emulsion-breaking liquid in the batches during such separation and settling. Discussion of preferred temperatures in continuous operations is given below.

With respect to the emulsion-breaking liquid, this may be any oil-soluble, at least partially water-soluble organic liquid consisting of carbon, hydrogen and oxygen of sufficiently low boiling point to facilitate its removal and recovery from the various phases and of sufficiently low viscosity

not to disturb seriously the various operations. Thus, any such oil-soluble, partially water-soluble liquid consisting of carbon, hydrogen, and oxygen and possessing four to about eight carbons per molecule is useful. By suitable boiling point, it is intended to signify a boiling point below the decomposition point of the sulfonates so that the diluent liquid may be eliminated from the product by vaporization. In general, this

10 signifies a boiling point not materially in excess of 400° F., inasmuch as the initial decomposition temperature of a sulfonate, such as calcium sulfonate, is in the neighborhood of 450° F. to 500° F.

15 This class of emulsion-breaking organic liquids, is at present best represented by the hexyl, amyl and butyl alcohols, for example, methyl isobutyl carbinol, iso-amyl alcohol ("pentasol" for example), and secondary butyl alcohol. These materials have suitable boiling ranges, and are partially water-soluble in water, for example, about 2% solubility in water for methyl isobutyl carbinol and about 12% for secondary butyl alcohol, and are preferentially oil-soluble. However,

20 other alcohols that may be employed are the heptanols and the octanols. Hereafter, the emulsion-breaking liquid ordinarily will be referred to as alcohol, with the above alcohols in mind, especially hexyl alcohol or butyl or secondary

25 butyl alcohol, the latter being now commonly employed by me in commercial operation. Examples of emulsion-breaking liquids other than alcohols are mesityl oxide, isopropyl acetate, isobutyl acetate, isopropyl ether, and methyl isobutyl ketone.

30 35 Having reference to the accompanying batch flow diagram of Fig. 1 and also to a particular crude alkali-metal sulfonate (Code No. 86-H) as an example of various crude sulfonates which have been successfully treated, a preferred method of procedure, which embodies the various aspects of this invention is set out below.

The foregoing crude alkali-metal (sodium) sulfonate (Code No. 86-H) contains about 4% water, 16% total sulfonates, 77% oil, and 3% inorganic salts. The inorganic salts are principally sodium sulfate with a very minor portion of sodium sulfite, both of which are to be removed by this method. The total sulfonate content consists of 14.5% mahogany acid soap and

45 50 1.5% green acid soap. It is desired to remove the green acid soap without loss of mahogany acid soap. It is desired also to remove excess oil and produce a concentrated calcium sulfonate containing 40% soap. It is further desired to convert any trace of sodium sulfonate appearing in the removed oil to calcium sulfonate in order that the removed oil may be used in formulating engine oils, rust preventive oils, etc.

60 65 *Purification stage.*—To the particular starting material, above described, water is added in an amount equal to approximately 20% of the crude stock, corresponding to 21.5% based on the oil-soap content of the crude stock. Preferably a 5% sodium chloride solution is employed because the sodium chloride serves efficiently to displace the sodium sulfate and the sodium sulfite so that the latter salts will come out in a settled brine layer. The less sodium chloride used, the less efficiently are the sulfites and sulfates eliminated.

70 75 While stronger concentrations of sodium chloride may be employed, 10% or 15% for example, to obtain greater removal of sulfates and sulfites, the additional cost is usually not considered justified. This is particularly because the amounts of sulfates and sulfites which

are not removed by employment of a 5% sodium chloride solution in the proper dosage are insufficient to detract seriously from the usefulness of the purified sodium sulfonate as such or as a raw material for making polyvalent-metal sulfonate.

To the crude sulfonate stock there is also added, between about 5% and about 15% of the selected emulsion-breaking organic liquid described, such as secondary butyl alcohol based on the crude stock. Hereinafter such material will be referred to merely as "the alcohol." In using secondary butyl alcohol, the alcohol is usually saturated with water and contains about 30% to 35% water. Appropriate allowance is made for such water content of the alcohol in formulating the treatment of a batch of stock.

In a particular instance, 32,203 gallons of the described crude sodium sulfonate stock containing about 16% total soap and about 4% water were pumped into a treating tank in admixture with 6,632 gallons of 5% sodium chloride solution containing 700 lbs. NaOH (the latter required to insure neutrality or slight alkalinity during the processing) and 4,858 gallons of the mentioned 65% to 70% secondary butyl alcohol. As is represented in the batch flow diagram of Fig. 1, the sodium chloride solution and the alcohol are introduced by pumps into the crude sulfonate stream on its way to a heater 10 in which the mixture is heated to about 150° F. and from which it is passed into a 60,000-gallon tank 12. When the entire batch is charged, it is agitated for 20 to 50 minutes to insure equilibrium between all components.

The heated and agitated mixture in tank 12 is then allowed to stand and settle for several hours, for example over night, or other appropriate period of time which may range from four or five hours up to any other desired time. During this interval the temperature gradually drops with this volume of material to about 140° F., the temperature, however, being at all times adequately high to assure good separation of a water (brine) phase which settles out in the bottom of the tank, as indicated, and carries with it all objectionable proportions of green acid soaps, sodium sulfite and sodium sulfate, and similar objectionable inorganic salts. Not only do the sulfites and sulfates separate in the lower brine layer, but the green acid sulfonates are also carried down in this brine layer because apparently they are preferentially soluble in the water of the brine layer, whereas the mahogany acid sulfonates which remain in the supernatant layer are preferentially soluble in the oil and in the oil-soluble alcohol.

The temperature range of 140° F. to 150° F., above indicated, has the further advantage that the separation of alcohol vapors is small. In practice such vapors as do accumulate in the top of the tank are conducted to an alcohol recovery system.

After sufficient standing and settling, the separated brine layer is withdrawn from the bottom of the tank. In the particular example above given, the brine layer measured 6,102 gallons, and the oil-soap-alcohol layer measured 39,551 gallons, both at 137° F. Preferably the withdrawn brine is passed to a still and the dissolved alcohol driven off and recovered.

Concentration stage.—The above described supernatant layer containing the oil, alcohol, and mahogany soap is passed from the tank 12 through a heater 14 and upon its way to the

heater is mixed with a quantity of tap water sufficient to unbalance the previous solvent relationship between the oil, soap, and alcohol so that upon further standing and settling any desired proportion of the excess oil in the soap-oil-alcohol layer is rejected depending on the amount of water added. In the specific instance 6,400 gallons of water equal to 20% of the original charge of crude stock was introduced. In the heater 14 the soap-oil-alcohol mixture with the added water is raised to a temperature of about 150° F. as before, and this mixture is then either returned to the tank 12 or passed to another tank 15 as indicated in the flow diagram, where it is agitated to insure equilibrium being established again.

In the tank 15, the heated mixture is again allowed to stand and settle over night, or for several hours, so that the oil rejected by reason of the change in the solvent relationship separates as a supernatant layer above a soap-oil concentrate containing the alcohol and the water. In the example described above, where the crude stock contained 77% oil, approximately 90% of the oil in the crude stock was rejected into the supernatant layer, while 10% of the oil in the charge remained in the underlying soap layer. In effect, oil appears to be rejected under a given set of conditions until the ratio of soap to oil in the soap containing phase satisfies the equilibrium requirements for that set of conditions (apparently without regard to the quantity of oil in the original charge of stock). Obviously, if the proportion of oil to soap is already below the equilibrium requirements, no oil will be rejected under that particular set of conditions. As more water and alcohol are added, however, a point will be reached where oil will be rejected. I have thus been able to concentrate alkali sulfonate to a degree where only 22 parts of oil remained for each 78 parts of sulfonate.

In the foregoing example of a batch being processed, the rejected oil layer gaged 26,085 gallons and the soap layer gaged 20,530 gallons, each at 140° F.

Conversion stage.—The aqueous soap concentrate (containing alcohol and some oil) which settles out in the tank 15 is next subjected to treatment to convert the alkali-metal, water-soluble, oil-soluble, mahogany sulfonate into a water-insoluble, oil-soluble, polyvalent-metal sulfonate. This is accomplished by passing the settled layer of the soap-oil concentrate from the bottom of the tank 15 to a heater 16 to restore its temperature, and by commingling this concentrate with a water solution of an appropriate polyvalent-metal salt. Commonly, calcium sulfonates are produced, and for this purpose a 30% to 50% solution of calcium chloride in water is used, this solution being commingled with the soap-oil concentrate as it is passed to the heater 16 whereby to raise the temperature of both the calcium chloride solution and the concentrate to about 150° F. If the rejected oil has been removed from the tank 15 (or tank 12) to some other tank, such as tank 18, the mixture heated in the heater 16 may be returned to the tank 15 (or the tank 12) or it may be passed to a conversion tank 20. As before, the heated mixture is allowed to stand and settle for several hours, or over night, whereby a water solution containing excess calcium chloride and sodium chloride settles out to leave a clear, supernatant layer of calcium sulfonate concentrate in oil together.

with the bulk of the alcohol and a limited amount of entrained or dissolved water.

In operating with the original 32,203 gallons of crude sulfonate of the above example, the amount of calcium chloride used to convert the mahogany sulfonate in the concentrate was 9,660 pounds which was dissolved in 1,453 gallons (12,108 pounds) of water.

In order to provide a consistent control of the concentration of the sulfonate in the end product, it has been found both easy and desirable to reject more oil than necessary during the rejection operation and then add back an appropriate amount of the same or another more desirable oil at a later stage to regulate the soap concentration in the final product. Where the concentrated sodium sulfonate is to be converted to a polyvalent metal sulfonate, the concentration adjusting oil may be added before, during, or after the conversion to the polyvalent-metal sulfonate. In the above example, 1,044 gallons of the rejected oil phase was pumped into the conversion tank following the transfer of the concentrated sodium sulfonate phase to the conversion tank. The total charge in the conversion tank was gaged to be 21,954 gallons after settling over night, of which 12,561 gallons was an oil-soap layer and 9,393 gallons was a brine layer.

Normally, in the conversion stage it might be expected that, in view of past experiences, the calcium or other polyvalent-metal sulfonate formed in such concentrated oil solution would result in the production of a very refractory water-in-oil emulsion. However, in conjunction with the described alcohol or other emulsion-breaking, oil-soluble, water-insoluble, organic-liquid compound consisting of carbon, hydrogen and oxygen, the phases break readily and separate sharply within a few hours to yield an underlying brine layer of sodium chloride and calcium chloride in water with a sharply defined supernatant layer of polyvalent-metal soap in concentrated condition in the oil present, together with the bulk of the emulsion-breaking liquid used and a proportion of water which is readily removable during a subsequent dehydration step. I have no particular theory regarding the action of the indicated class of organic compound. Apparently the function of the alcohol, or other emulsion-breaking liquid, is not so much that of a selective solvent as that of breaking up an otherwise stable oil-continuous emulsion, or, possibly, that of preventing formation of such an emulsion.

The calcium soap-oil-alcohol layer is then passed to a still 22 to distill off the alcohol, which is recovered and sent to storage, and to dehydrate the oil-soap concentrate to yield a finished product which may be placed in storage, as in a receptacle 24, either with or without filtering or other further treatment.

Inasmuch as the excess oil rejected in the concentration stage in tank 15 may contain a very small amount of mahogany soap, this soap should be converted into calcium or other polyvalent-metal soap. Therefore, such oil, having been passed for example to the tank 18 for treatment, is recirculated through a heater 25 in admixture with the excess calcium chloride in the water solution drawn from the conversion tank 20, and the temperature again brought up to about 150° F. The heated mixture is allowed to stand in the tank 18 until the water solution separates in the bottom and leaves a supernatant oil layer containing the small amount of resultant calcium sulfonate. Such oil, which is commonly of lubri-

cating viscosity, is useful in lubricating, rust-preventing, and other petroleum compositions and is therefore dehydrated and recovered as a valuable product.

5. By finishing the converted soap layer and the converted rejected oil layer separately by adding $\text{Ca}(\text{OH})_2$ (calcium hydroxide) to insure alkaline products, distilling to recover alcohol and remove water, finally heating to approximately 10 300° F., and then filtering with the aid of a small amount of diatomaceous earth, a yield of alkaline calcium sulfonate concentrate of 10,045 gallons having a sulfated ash value of 6.68% was obtained, and a yield of "by-product" (rejected) oil of 19,743 gallons having a sulfated ash value of 0.12% was obtained. These recoveries correspond to 31.2% and 61.3%, respectively, based on the original charge of crude sodium sulfonate.
10. Referring to various aspects of the above-described treatment, in the purification step the dosages of water (or NaCl solution) and emulsion-breaking liquid are best selected with respect to each other. It is apparent from Figs. 2, 3, and 4 that, for each alcohol dosage in the range of 5% to 15% based on the oil-soap content of the stock, there is an appropriate range of water content of the mix (the sum of both the water present in the stock and the water added) for any given 15 alcohol content. This appropriate water content of the mix will usually be found in the range of 10% to 60% water based on the oil-soap content of the stock. Furthermore, in the appropriate water range for any given alcohol dosage, there will be a somewhat narrower preferred range of water content, as is to be expected from the fact that with water contents below and above the appropriate range, no brine phase is produced. For example, as indicated in Fig. 2, an alcohol 20 dosage of 12.5% and a total water content of 21% gave about the same extraction of salts and other impurities (such as green acid soap) as an alcohol dosage of 6.25% and a total water content of 34%. In the first case the yield of brine layer 25 was 8.5% as compared with 10.0% in the second, but the brine in the first case was more concentrated. (Other crude sulfonates will have somewhat different optimum ranges but the appropriate range will be found within the general order of magnitude indicated for the stock shown above.) While the extraction of impurities was about the same in the two cases, it will be noted that in the first case only a brine phase separated on settling, yielding two layers, whereas in 30 the second case a rejected oil layer appeared on top of the concentrated and purified soap layer, along with the brine layer on the bottom, thereby yielding three layers. Sometimes it is preferable to avoid simultaneous rejection of oil along with the brine, as for example in one method of operating a continuous extraction column, but in the 35 batch method, simultaneous separation of oil is of little consequence, and the dosages of alcohol and water are chosen to give the optimum extraction of salts and other water-soluble impurities regardless of simultaneous rejection of oil from the soap phase.
40. In the event sufficient oil is rejected under conditions of optimum extraction of water-soluble impurities, then subsequent rejection of oil is obviously unnecessary and the concentration step is therefore completed along with the purification. On the other hand, if the purification conditions chosen do not reject the desired portion of oil, then the brine phase is removed 45
45. 50. 55. 60. 65. 70. 75.

and additional water is then added to bring up the total water used (including water originally in the stock) to the place on the curve where the desired amount of oil is rejected. Instead of adding water, more alcohol, or both alcohol and water, may be added to cause additional rejection of oil. If the purification and concentration are to be conducted separately, the brine settled in the purification step should be removed before any appreciable additional water or alcohol is added, lest the brine redissolve in the mix.

Often, it is desirable to have present at least enough alcohol to saturate or approximately saturate the water present, in order to get good separation. This is true especially where high volume ratios of water (such as higher than the indicated 60% of water based on the oil-sulfonate content) are used, inasmuch as such saturation provides a good means for alcohol control. Otherwise, good alcohol contents are found in the range of 10% to 50% of the total water content, or within a range of about 3% to 20% based on the oil-sulfonate content. The economically and operatively preferred range, if not the most efficient range, is from 5% to 15% of alcohol or other emulsion-breaking liquid, based on the oil-sulfonate content.

In the event the crude sulfonate as received contains too much water to give a brine phase upon the addition of the specified alcohol, the excess water is removed by evaporation substantially into or, if desired, until the amount remaining corresponds to the working range for the usual alcohol dosage of 5% to 15%. The evaporation may be by distillation or by heating and air blowing. In general the most satisfactory procedure is to remove most of the water and then add back the desired amount as the stock is processed in accordance with this invention.

In purifying crude sulfonates containing a high ratio of soap to oil, it has been found convenient and efficient to add a substantial amount of lubricating oil to the stock or to the mix being treated for the two-fold purpose of reducing the viscosity and reducing the solvent power of the soap phase for water-soluble impurities. As long as the oil added is of suitable quality, this entails little or no hardship because this amount of oil is easily rejected, after the removal of the brine layer, by addition of water or alcohol and thereby recovered. In this instance the rejected oil may be recycled without removal of dissolved or entrained alcohol and water.

In the foregoing example of a commercial operation of the process, the method of treatment is batchwise for each of the purification, concentration, and conversion steps. In many instances, however, particularly where the demand for the finished sulfonate is steady and of sufficient magnitude, it is desirable to operate the process in a continuous manner.

Figure 5 illustrates continuous operation of the process with single stage treatment by the reactants. Fig. 6 illustrates continuous operation of the process with countercurrent flow of reactants. Many modifications and combinations of the steps will be readily apparent to those skilled in the art from the disclosures contained herein. For example, multiple treatments may be given at each step of the process of Fig. 5, when necessary to obtain complete results.

Referring to Fig. 5, the crude sulfonate in a storage tank 31 is fed by a pump 32 at a controlled rate through a line 33 to the processing system. The alcohol or other emulsion-breaking

liquid specified herein is charged at a controlled rate through a pump 34 into the line 33 through which the crude sulfonate is flowing. Water or aqueous sodium chloride solution is charged through a pump 35 at a controlled rate also into the line 33 through which the crude sulfonate and alcohol are flowing. The mixture of crude sulfonate, alcohol and water flows into a mixer 36 which is equipped with suitable agitators and baffles to insure chemical equilibrium of the reactants and reaction products as they emerge from the top of the mixer 36 through a line 37 and flow into a settling vessel or "purifier" 38. In this vessel, the soda brine phase containing sodium sulphite, sodium sulphate and other water-soluble impurities, such as green acid soap, settles to the bottom and the purified sulfonate rises to the top. The settled soda brine is withdrawn through a valve 39 actuated as by a suitable liquid level control device (at the interface) in vessel 38 and sent to an alcohol recovery still where the alcohol is recovered, and the brine is then discarded.

The purified sulfonate practically free of brine droplets overflows from the tank 38 to a line 40 through which it is forced by a pump 41 into a mixer 42. Water is charged by a pump 43 into the line 40 through which the purified sodium sulfonate is flowing. Mixer 42 is equipped with suitable agitators and baffles to insure equilibrium between the reactants and reaction products by the time they emerge through an upper line 44 and flow into a settling vessel or oil rejector 45. The mixture entering the vessel 45 stratifies into a concentrated soap and oil layer settling to the bottom and a rejected oil layer rising to the top and removed through an upper line 45a. The concentrated soap layer is transferred from the bottom of the vessel 45 through a lower line 46 by a pump 47 and a valve 48 which are controlled by a suitable liquid level device in the settling vessel 45. A relatively concentrated calcium chloride solution is charged by a pump 49 into the line 46 through which the concentrated sodium sulfonate is flowing, this stream passing to a converter or mixer 50 equipped with suitable agitators and baffles to insure thorough equilibrium between the reactants and reaction products when the mixture emerges at the top through a line 51 by which it is carried into converted concentrate settling vessel 52. The mixture entering the settling vessel 52 stratifies into two layers; namely, (1) an aqueous phase containing sodium chloride formed by metathesis from the calcium chloride, excess calcium chloride, and other water soluble impurities such as the last portions of green acid soaps, and (2) an oily phase consisting of oil, converted sulfonate, and the major portion of the alcohol carried through the process to this point.

The oily phase rises to the top of the settling vessel 52 and overflows through a line 53 from which it is charged by pump 53a to an alcohol recovery still 54. A slurry of calcium hydroxide is prepared in an agitator 55 and pumped via a line 55a and a pump 56 into the line 53 carrying the converted soap layer to the alcohol recovery still 54. In practice the still 54 is duplicated, one still being used for distillation while the other is being charged, or the converted soap layer supplied by the line 53 is accumulated in an intermediate storage tank (not shown) while a batch is being run down in the still 54, or the still 54 may be of the continuous type consisting of a

tubular heater and fractionating tower. Either steam or vacuum or both may be used in the still to aid removal of the last traces of alcohol and water from the converted soap layer. The converted soap layer is finally heated to a temperature in the neighborhood of 300° F. and then filtered in a filter press 57 and sent to storage 58. To aid filtration of the dehydrated calcium soap concentrate, a small amount of diatomaceous earth (e. g. Supercel Hyflo), such as 1% to 2% by weight, is added before filtration. The alcohol from the converted soap layer is recovered in apparatus 59 for reuse in the process.

Inasmuch as the process depends upon the presence of water in the various steps, it is unnecessary to remove the dissolved water from the alcohol recovered from any step in the process. The water layer from the condenser of the alcohol recovery system is occasionally rerun to concentrate the alcohol.

Since the rejected oil layer rising in the settling and rejecting vessel 45 contains a small amount of sodium mahogany soap which should be converted, such oil is passed by the line 45a from the vessel 45 to a mixer 60 equipped with suitable agitators and baffles to insure equilibrium between reactants and reaction products. Since the bottom aqueous layer in the settling vessel 52, resulting from the reaction of the concentrated soda soap with calcium chloride solution, contains excess calcium chloride, this brine layer also is pumped to the mixer 60 for the purpose of reaction with the soda soap in the rejected oil. This transfer is made by way of a line 61, a valve 61a, and a pump 61b controlled by a suitable liquid level device (not shown) in the vessel 52. The brine from the line 61 is delivered to the line 45a through which the rejected oil is being forced to the mixer 60 by a pump 60a. Following reaction between calcium chloride and the sulfonate of the rejected oil in the mixer 60, the reacted materials leave the mixer 60 by a line 62 and flow into a settling vessel 63 where stratification occurs to yield a calcium brine layer on the bottom and a converted oil layer on top. The converted oil layer is delivered by a line 64 and a pump 64a to a still 65 for recovery of contained alcohol and dehydration of the oil. The calcium brine layer is withdrawn from the bottom of the vessel 63 through suitable level control valves and pumps (not shown) and is processed for recovery of dissolved alcohol and then discarded. A small portion of this brine can be used in the agitator 55, if desired, in making a calcium hydroxide slurry to be added either to the concentrated soap layer being charged to the still 54 or to the converted, rejected oil layer charged to the still 65. The converted by-product oil layer, in which any trace of soap carried over from the concentration of the soda soap in the settling and rejecting vessel 45 has now been converted in the vessel 63 to calcium soap, when being processed in the still 65 may contain a slurry of calcium hydroxide suspended in oil or water or brine containing calcium chloride added from the agitator 55, as above indicated, or from an agitator 66 by a pump 67 via a line 68, to the charge going into the still 65. In this still, both dissolved alcohol and water are removed by heating to a temperature in the neighborhood of 300° F. with the use of vacuum or steam. The liberated alcohol is recovered in appropriate apparatus 69 for reuse in the process. The dehydrated alcohol-free oil is filtered and sent to storage 70 for use in blending lubricating

oils, rust preventives, and the like, or it may be further refined to produce white oils.

In the operation illustrated in Fig. 5, the temperature is preferably higher than in the batch method illustrated in Fig. 1, to insure efficient operation of the continuous settling vessels; namely, in the neighborhood of 180° F. to 200° F. as previously indicated. Appropriate heaters (not shown) are employed in much the same way as shown in Fig. 1. Care is taken to avoid loss of alcohol by vaporization, even to the point of operating all mixers and settlers under pressure.

Alcohols boiling higher than secondary butyl alcohol, especially methyl isobutyl carbinol, are often preferred in the continuous method of operating the process at the higher temperature. Methyl isobutyl carbinol is available commercially at only slightly higher cost than secondary butyl alcohol and is readily recovered from the various brines and products, its boiling point being 267° F. at atmospheric pressure. Also the solubility of the higher boiling alcohols in water is less, methyl isobutyl carbinol being soluble in water to the extent of only about 2% as compared with about 12% for secondary butyl alcohol.

The lower solubility in water of amyl and hexyl alcohols is also desirable in the countercurrent methods of operating the process, about to be described, particularly in the countercurrent washing of the rejected oil to reduce dissolved soap content, as well as in the purification and conversion steps where water or aqueous solutions are passed in countercurrent to the oily phases. Higher temperatures, e. g. 180° F. to 200° F., with operation under pressure are employed in such countercurrent operations in much the same manner as for the process of Fig. 5.

Fig. 6 illustrates a countercurrent, continuous operation of the process, the crude sulfonate in storage tank 71 being fed by a pump 72 at a controlled rate through a line 73 to the processing system. The alcohol or other emulsion-breaking liquid specified herein is charged at a controlled rate by a pump 74 into the line 73 through which the crude sulfonate is flowing. The mixture of stock and alcohol enters the lower portion of a countercurrent extraction column 75 while water or aqueous sodium chloride is charged at a controlled rate by a pump 76 and a line 77 into the upper portion of the extraction column 75. As the mixture of stock and alcohol works its way up the column, the water or sodium chloride solution works its way downward and extracts from the stock the water soluble impurities such as sodium sulphate, sodium sulphite and the green acid soaps. The brine thus formed settles in the bottom of the column 75 and is withdrawn through a valve 78 which is actuated by a suitable level control in the column 75 and is sent to a still for recovery of the alcohol dissolved therein. The extracted or purified stock containing the bulk of the alcohol introduced into the stream of stock in the line 73, passes out of the top of the column 75 through a line 79 and is forced by a pump 80 through a line 81 either directly into an oil rejection or extraction column 82 or via an agitator 83 by proper manipulation of valves 84, 85, and 86. Water is charged into the system at a controlled rate by a pump 88 through a line 89 by opening a valve 90, and/or water is charged at a controlled rate into the top section of the column 82 by a pump 91 via a valve 92 and a line 93. Water charged

through the line 89 mixes with the purified stock and alcohol in the line 81. This mixture may be thoroughly agitated by closing the valve 84 and opening the valves 85 and 86 and forcing the mixture through the agitator 83 which provides sufficient agitation to insure equilibrium between the reactants and the reaction products; this usually being preferred when water is introduced by the pump 88 and line 89 into the stream being processed. Sometimes it is desirable to introduce all of the water via the pump 91 and line 93 into the top section of the column 82, in which case the stock flowing in the line 81 is made to bypass the agitator 83 by opening the valve 84 and closing the valves 85 and 86. The water introduced into the top section of the extraction column 82 via line 93 washes countercurrently the rejected oil which is rising upward in the column 82, and also causes rejection of oil from the purified stock in the lower section of the column 82.

In other words, partial or fairly complete rejection of oil may be accomplished by the water introduced along with the stock via the line 81 and agitator 83, while any water introduced into the upper section of the column 82 via the line 93 serves to wash out soap dissolved or entrained in the rejected oil rising from the bottom of the column.

The soda soap solution now concentrated with respect to oil settles to the bottom of the column 82 and is removed via a valve 94 and a pump 95 which are actuated by a suitable level control device (not shown) in the lowest section of the column 82. The concentrated soda soap solution is forced by the pump 95 via a line 96 into the bottom section of a conversion or extraction column 97, going through an agitator 98 or by-passing this agitator by proper operation of valves 99, 100, and 101. Aqueous calcium chloride solution of suitable concentration is charged into the column 97 by a pump 102 via a line 103 into the top section of the extraction column 97, or by a pump 104 into the bottom section of the column 97 in admixture with the concentrated soap stock moving in the line 96. If calcium chloride solution is introduced into the line 96, it is desirable to agitate the resulting mixture thoroughly before it reaches the column 97 by sending it through the agitator 98 by opening the valves 100 and 101 and closing the valve 99. If a portion of the calcium chloride solution is premixed with the stock in the agitator 98 and introduced into the bottom section of the column 97, via the line 96 along with the stock, any additional calcium chloride solution introduced by the pump 102 moves countercurrent to the reacted oily soap phase rising in the column 97 and serves to complete the conversion of sodium soap to calcium soap. The converted soap phase flows out the top of column 97 via a line 105 and a pump 106 and is sent to intermediate storage tank 107 whence it is sent to a still 108, for recovery of alcohol in apparatus 109, and dehydration before filtering. Lime or other reagents may be added to the stock in the tank 107 before it is charged to the still 108 by a pump 110. Diatomaceous earth which serves as a filter aid is added before, during, or after the distillation and dehydration. The dehydrated concentrate is passed through a filter 111 and the finished calcium sulfonate concentrate is sent to storage 112.

The spent or partially spent calcium chloride brine resulting from the conversion of the soda soap to calcium soap in the agitator 98 and con-

version or extraction column 97, settles to the bottom of the column 97, whence it is withdrawn through a valve 113 and pump 114 and sent to a still for recovery of dissolved alcohol.

- 5 The oil rejected in the rejection column 82 rises upward and settles practically free of entrained water and soap in the top of the column. However it contains a very small proportion of dissolved mahogany soap which should be converted. Therefore, the rejected oil is passed from the top of the column 82 via a line 115 and a pump 116 into a treating column 118, and calcium chloride solution, which may conveniently be the partially spent brine layer settling to the bottom 10 of extraction column 97, also is introduced into the top of column 118 via a pump 119 and a line 120, or into the bottom of the column 118 via a pump 121 and a line 122. Any calcium chloride solution introduced via pump 119 is best mixed 15 with the rejected oil phase flowing in the line 115 by passing the mixture through an agitator 123 before it goes into the treating column 118. The operation of the conversion of the small amount of soda soap carried over in the by-product oil 20 flowing from the top of the rejection column 82 is similar to the conversion of the concentrated soda soap phase settling to the bottom of the column 82 and converted and separated in the column 97.
- 25 The converted, rejected oil in the column 118 rises to the top and is sent via a pump 124 and a line 124a to intermediate storage 125, whence it is charged by a pump 126 to a still 128 for alcohol recovery in apparatus 129 and for dehydration 30 before filtering. After passing through a filter, this converted, rejected oil is sent to storage for use as a lubricant, or in compounding rust preventives or lubricants, or the like. The brine phase in the column 118 settles to the bottom 35 and is withdrawn via a valve 131 and a pump 132 which are controlled by a suitable liquid level device (not shown) in the lowest portion of the column 118. This brine is distilled for alcohol recovery and is finally discarded.
- 40 It is to be understood that this process, whether batch or continuous, is equally applicable to the treatment of alkali-metal sulfonate-oil concentrates of commerce which contain around 30% to 60% sulfonates and 40% to 70% oil with impurities in the form of green acid soaps, sulfates, sulfites, and the like.
- 45 While the purified polyvalent metal petroleum sulfonates or mahogany soaps obtained in accordance with this invention are usually calcium products, the invention, nevertheless extends to the preparation of other alkaline earth metal sulfonates, especially barium and strontium salts. These may be prepared with water-soluble salts of barium and strontium as readily as the calcium product is produced. The process is also applicable to the production of other water-insoluble, oil-soluble sulfonates, and these may include the mahogany acid salts of aluminum, zinc, magnesium, lead, cobalt, nickel, and the like.
- 50 Concentrates of the above nature may be put to various uses. For example, the addition of 5% to 20% of the above concentrate to calcium, aluminum, barium, magnesium, zinc, and lithium base greases, respectively, has both imparted markedly improved anti-rusting properties and reduced tendencies to bleeding or separation of the oil content of the greases on standing.

- While the purified polyvalent metal petroleum sulfonates or mahogany soaps obtained in accordance with this invention are usually calcium products, the invention, nevertheless extends to the preparation of other alkaline earth metal sulfonates, especially barium and strontium salts. These may be prepared with water-soluble salts of barium and strontium as readily as the calcium product is produced. The process is also applicable to the production of other water-insoluble, oil-soluble sulfonates, and these may include the mahogany acid salts of aluminum, zinc, magnesium, lead, cobalt, nickel, and the like.
- Concentrates of the above nature may be put to various uses. For example, the addition of 5% to 20% of the above concentrate to calcium, aluminum, barium, magnesium, zinc, and lithium base greases, respectively, has both imparted markedly improved anti-rusting properties and reduced tendencies to bleeding or separation of the oil content of the greases on standing.
- Rust preventives constitute another important phase of use of the present product. These are

obtained by diluting the appropriate polyvalent-metal sulfonate concentrate with appropriate carriers, such as any mineral oil lubricating fraction suitable for the ultimate use of the product. Commonly, such dilution will yield a sulfonate content between about .05% and about 6% in the blended product. Ordinarily a satisfactory working proportion is about 3% of sulfonate, or within a range of about 2% to about 4%.

Another important use of the purified, polyvalent-metal sulfonate of this invention is in connection with the production of lubricating oils for severe service, internal combustion engines, such as aircraft and other heavy-duty engines, including diesel engines. Here the sulfonate may be present in proportion to impart rust-preventive characteristics or for other purposes, including promotion of detergent and wear-reducing characteristics. For these purposes, typical lubricating oils may contain from about 0.5% to as much as 10%, for example 3%, of the purified alkaline earth metal sulfonates of this invention, together with such other additive constituents as may be deemed desirable. Depending upon the ends sought, such other materials may include sulfurized alcohols, sulfurized hydrocarbons, thiophosphates, phenolic thioethers, phosphites, metal derivatives of these materials, various oil-soluble detergent soaps, such as the calcium soaps, and similar metal soaps of synthetic carboxylic acids obtained from the oxidation of paraffinic hydrocarbons, and kindred materials known in the lubricating industry.

When any of the products above described are to be used under conditions where foaming is apt to be encountered, purified sulfonates may be produced, as above described, by employing the indicated octyl alcohol and terminating the subsequent expulsion of the octyl alcohol so as to leave around 0.5% to 2% of octyl alcohol in the oil-sulfonate solution whereby to impart anti-foaming characteristics. The same will be true of any other organic solvent which is employed and possesses anti-foaming characteristics. I have also found that the presence of 0.25% to 2% of octyl alcohol or other high molecular weight alcohol in the finished lubricant increases very greatly the effectiveness of the sulfonate addition in combating corrosion from hydrobromic acid. For example, the addition of 2.5% calcium sulfonate to a heavy-duty motor oil containing 0.75% calcium soap of oxidized petroleum acids and 0.75% calcium salt of tertiary amyl phenol sulfide was sufficient to protect the crankcase interior of engines against rusting from moisture condensation, but was insufficient to protect against dilute aqueous hydrobromic acid. The addition of 0.75% of octyl alcohol (2-ethylhexanol) to the foregoing oil containing 2.5% sulfonate, as described, gave perfect protection against hydrobromic acid corrosion.

While I have described my process as being applicable to petroleum sulfonates produced by sulfuric acid treatment of petroleum fractions particularly those in the lubricating oil range, my process is also applicable to sulfonates produced synthetically by sulfonation of hydrocarbons or other compounds from coal tar products or any other source. Also, my process is applicable to sulfates (often called sulfonates) produced by reacting sulfuric acid or sulfur trioxide with alcohols and/or unsaturated compounds belonging to the classes of hydrocarbons, acids, esters, ketones, ethers, glycerides, waxes, etc.

Inasmuch as variations of the different fea-

tures of the generic invention herein disclosed will no doubt occur to those skilled in this particular art, it is intended to cover all modifications which fall within the scope of the patent claims.

I claim as my invention:

1. The process of treating a material consisting of a major proportion of hydrocarbon oil containing alkali metal mahogany sulfonates, alkali metal green acid sulfonates and water-soluble inorganic sulfate and sulfite, which comprises: forming a mixture consisting essentially of said hydrocarbon oil, said alkali metal mahogany sulfonates, said alkali metal green acid sulfonates, said water-soluble inorganic sulfate and sulfite, at least 10 parts by volume of water per 100 parts by volume of said hydrocarbon oil and sulfonates and at least 5 parts by volume per 100 parts by volume of said hydrocarbon oil and sulfonates of a hydrocarbon oil-soluble emulsion breaking liquid selected from the group consisting of butyl, amyl and hexyl alcohols, the amounts of said water and said emulsion breaking liquid being sufficient to produce three separable phases, a concentrated mahogany sulfonate phase containing hydrocarbon oil, water and emulsion breaking liquid, a hydrocarbon oil phase rejected from said concentrated mahogany sulfonate phase and an aqueous phase containing alkali metal green acid sulfonates and water-soluble inorganic sulfate and sulfite; and separating said three phases from each other.

2. The process as defined in claim 1 in which the temperature of said hydrocarbon oil phase and said concentrated sulfonate phase during said separating is between 140° F. and 200° F.

3. The process as defined in claim 1 in which the emulsion breaking liquid is a butyl alcohol.

4. The process as defined in claim 1 in which the emulsion breaking liquid is secondary butyl alcohol.

5. The process as defined in claim 1 in which the emulsion breaking liquid is hexyl alcohol.

6. The process as defined in claim 1 in which a water-soluble polyvalent metal salt is mixed with the separated concentrated mahogany sulfonate phase to convert the alkali metal mahogany sulfonate therein to a polyvalent metal mahogany sulfonate and produce a separable aqueous phase and a concentrated polyvalent metal mahogany sulfonate phase containing hydrocarbon oil and minor proportions of water and emulsion breaking liquid, and the separable aqueous phase is separated from said concentrated polyvalent metal mahogany sulfonate phase.

7. The process of treating a material consisting of a major proportion of hydrocarbon oil containing alkali metal mahogany sulfonates, alkali metal green acid sulfonates and water-soluble inorganic sulfate and sulfite, which comprises: forming a mixture consisting essentially of said hydrocarbon oil, said alkali metal mahogany sulfonates, said alkali metal green acid sulfonates, said water-soluble inorganic sulfate and sulfite, sodium chloride, at least 10 parts by volume of water per 100 parts by volume of said hydrocarbon oil and sulfonates and at least 5 parts by volume per 100 parts by volume of said hydrocarbon oil and sulfonates of a hydrocarbon oil-soluble emulsion breaking liquid selected from the group consisting of butyl, amyl and hexyl alcohols, the amounts of said water, said sodium chloride and said emulsion breaking liquid being sufficient to produce three separable phases, a concentrated mahogany sulfonate phase contain-

ing hydrocarbon oil, water and emulsion breaking liquid, a hydrocarbon oil phase rejected from said concentrated mahogany sulfonate phase and an aqueous phase containing alkali metal green acid sulfonates, water-soluble inorganic sulfate and sulfite and a major proportion of said sodium chloride; and separating said three phases from each other.

8. The process as defined in claim 7 in which a water-soluble polyvalent metal salt is mixed with the separated concentrated mahogany sulfonate phase to convert the alkali metal mahogany sulfonate therein to a polyvalent metal mahogany sulfonate and produce a separable aqueous phase and a concentrated polyvalent metal mahogany sulfonate phase containing hydrocarbon oil and minor proportions of water and emulsion breaking liquid and the separable aqueous phase is separated from said concentrated polyvalent metal mahogany sulfonate phase.

9. The process of treating a material consisting of a major proportion of hydrocarbon oil containing alkali metal mahogany sulfonates, alkali metal green acid sulfonates and water-soluble inorganic sulfate and sulfite, which comprises: forming a mixture consisting essentially of said hydrocarbon oil, said alkali metal mahogany sulfonates, said alkali metal green acid sulfonates, said water-soluble inorganic sulfate and sulfite, at least 10 parts by volume of water per 100 parts by volume of said hydrocarbon oil and sulfonates and at least 5 parts by volume per 100 parts by volume of said hydrocarbon oil and sulfonates of a hydrocarbon oil-soluble emulsion breaking liquid selected from the group consisting of butyl, amyl and hexyl alcohols, the amounts of said water and said emulsion breaking liquid being sufficient to produce an aqueous phase containing alkali metal green acid sulfonates and water-soluble sulfate and sulfite, and a separable hydrocarbon oil-sulfonate phase containing hydrocarbon oil, water, emulsion breaking liquid and alkali metal mahogany sulfonates; separating said hydrocarbon oil-sulfonate phase from said aqueous phase; mixing with the separated hydrocarbon oil-sulfonate phase an additional amount of a liquid selected from the group consisting of water, and said emulsion breaking liquid, the amounts of said water and said emulsion breaking liquid in the resulting mixture being sufficient to produce a concentrated mahogany sulfonate phase containing alkali metal mahogany sulfonates, hydrocarbon oil, water and emulsion breaking liquid and a separable hydrocarbon oil phase rejected from said concentrated mahogany sulfonate phase; and separating said hydrocarbon oil phase from said concentrated mahogany sulfonate phase.

10. The process as defined in claim 9 in which the emulsion breaking liquid is a butyl alcohol.

11. The process as defined in claim 9 in which the emulsion breaking liquid is secondary butyl alcohol.

12. The process as defined in claim 9 in which the emulsion breaking liquid is hexyl alcohol.

13. The process of treating a material consisting of a major proportion of hydrocarbon oil containing alkali metal mahogany sulfonates, alkali metal green acid sulfonates and water-soluble inorganic sulfate and sulfite, which comprises: 70

forming a mixture consisting essentially of said hydrocarbon oil, said alkali metal mahogany sulfonates, said alkali metal green acid sulfonates, said water-soluble inorganic sulfate and sulfite, said sodium chloride, at least 10 parts by volume of water per 100 parts by volume of said hydrocarbon oil and sulfonates and at least 5 parts by volume per 100 parts by volume of said hydrocarbon oil and sulfonates of a hydrocarbon oil-soluble emulsion breaking liquid selected from the group consisting of butyl, amyl and hexyl alcohols, the amounts of said water, said sodium chloride and said emulsion breaking liquid being sufficient to produce an aqueous phase containing alkali metal green acid sulfonates, water-soluble sulfate and sulfite and said sodium chloride, and a separable hydrocarbon oil-sulfonate phase containing hydrocarbon oil, water, emulsion breaking liquid and alkali metal mahogany sulfonates; separating said hydrocarbon oil-sulfonate phase from said aqueous phase; mixing with the separated oil-sulfonate phase an additional amount of a liquid selected from the group consisting of water, and said emulsion breaking liquid, the amounts of said water, said sodium chloride and said emulsion breaking liquid in the resulting mixture being sufficient to produce a concentrated mahogany sulfonate phase containing alkali metal mahogany sulfonates, hydrocarbon oil, water and emulsion breaking liquid and a separable hydrocarbon oil phase rejected from said concentrated mahogany sulfonate phase; and separating said hydrocarbon oil phase from said concentrated mahogany sulfonate phase.

14. The process as defined in claim 13 in which the emulsion breaking liquid is a butyl alcohol.

15. The process as defined in claim 13 in which the emulsion breaking liquid is secondary butyl alcohol.

16. The process as defined in claim 13 in which the emulsion breaking liquid is hexyl alcohol.

17. The process as defined in claim 13 in which a water-soluble polyvalent metal salt is mixed with the separated concentrated mahogany sulfonate phase to convert the alkali metal mahogany sulfonate therein to a polyvalent metal mahogany sulfonate and produce a separable aqueous phase and a concentrated polyvalent metal mahogany sulfonate phase containing hydrocarbon oil and minor proportions of water and emulsion breaking liquid and the separable aqueous phase is separated from said concentrated polyvalent metal mahogany sulfonate phase.
